UNITED STATES PATENT OFFICE.

JOSEPH H. LAPHAM AND OWEN T. LAPHAM, OF CLEVELAND, OHIO.

WASH-BOARD PLATE.

SPECIFICATION forming part of Letters Patent No. 339,667, dated April 13, 1886.

Application filed December 14, 1885. Serial No. 185,590. (No model.)

To all whom it may concern:

Be it known that we, JOSEPH H. LAPHAM and OWEN T. LAPHAM of Cleveland, in the county of Cuyahoga and State of Ohio, have 5 invented a certain new and Improved Wash-Board Plate; and we do hereby declare that the following is a full, clear, and complete description thereof.

The above-mentioned improvement in wash-boards relates to the peculiar configuration of the surfaces of the zinc plate used for the rubbing-surfaces of the board, as hereinafter fully described, and shown in the annexed drawings, forming a part of this specification, in which—

15 Figure 1 represents a portion of the frame of a wash-board having applied thereto the improved metal plate, of which one side is shown. Fig. 2 is a view of the opposite side of the plate. Fig. 3 is an edge view of the 20 plate.

Like letters of reference refer to like parts in the several views.

The wood-work or frame of the wash-board is or may be like that of ordinary wash-boards; 25 hence a description thereof is not essential in this place.

A is the zinc plate of the board, and the surface shown in Fig. 1 corresponds to the side B in Fig. 3, in which Care prominent ribs extending across the plate. Midway between said ribs and longitudinally therewith is a 30 rib, D, of slight elevation as compared with the ribs C.

In the groove or channel between the ribs 35 C and D are struck up swells E, at regular distances apart and partly in the side of the ribs C and D, as shown in Fig. 1. Between the said swells are narrow incavations F, thereby forming an alternating series of swells 40 and incavations or depressions across the plate between the ribs C and D, forming in the face of the plate a vertical succession of ribs or corrugations and a transverse series of alternating swells and depressions, substantially as 45 shown in Fig. 1. As a consequence, the op-

posite side of the plate will be negative that of the side above described, as shown in Fig. 2, in which are deep grooves or channels G, conforming to the ribs C in Fig. 3, and ribs a and b corresponding to the ribs a and b in Fig. 50 3; also in the ribs b is a series of depressions, e, the opposite sides of the swells E, above described.

It will be obvious from the above description of the plate that one side thereof consists, 55 mainly, of ribs a considerable distance apart, forming a coarse corrugated surface adapted for wasbing and rubbing heavy, large, and coarse articles, and having between the said ribs numerous depressions for retaining the 60 wash-water while the said articles are being rubbed thereon, whereas, on the opposite or negative side of the plate, Fig. 2, the ribs are much closer together, forming a finer corrugated surface, and in each alternate rib a series 65 of alternating elevations and depressions. This latter side, for having the ribs close together, is adapted for washing finer and more delicate articles than could be rubbed with safety on the side shown in Fig. 1, thereby rendering the wash-board more useful for washing coarse, heavy, and lighter finer articles. 70

What we claim as our invention, and desire to secure by Letters Patent, is—

In wash-boards, a metal plate having on one 75 side thereof large transverse ribs C, and, alternating therewith, ribs D, of slight elevation as compared with said ribs C, and in the grooves between the ribs an alternating series 80 of swells and depressions, and in the reverse side of the plate, grooves G, ribs a and b, and having in the ribs b a series of depressions, substantially as described.

In testimony whereof we affix our signatures in presence of two witnesses.

JOSEPH H. LAPHAM.
OWEN T. LAPHAM.
